UNITED STATES PATENT OFFICE.

MARK A. SHELDON, OF DETROIT, MICHIGAN.

DESIGN FOR A HOLDER FOR CURLING-IRONS.

SPECIFICATION forming part of Design No. 23,137, dated March 20, 1894.

Application filed February 23, 1894. Serial No. 501,308. Term of patent 7 years.

To all whom it may concern:

Be it known that I, MARK A. SHELDON, a citizen of the United States, residing at Detroit, in the county of Wayne and State of Michigan, have invented and produced a new and original Design for a Curling-Iron Holder, of which the following is a specification, reference being had therein to the accompanying drawings.

In the drawings, Figure 1 is a front elevation of my newly designed curling iron holder and Fig. 2 is a side elevation thereof.

The design consists of the cross shaped body comprising the stem A and the laterally extending arms B at the top, the bowl C hav-

ing the curved bottom and extending entirely from one side at the lower end of the stem A and the rearwardly bent ring shaped top D, the bend starting from at or near the middle of the arms.

What I claim is—

The design for a curling iron holder, substantially as shown and described.

In testimony whereof I affix my signature in presence of two witnesses.

MARK A. SHELDON.
